UNITED STATES PATENT OFFICE.

MAX NOVICK, OF NEW YORK, N. Y.

ADJUSTABLE BED.

1,306,614.

Specification of Letters Patent. Patented June 10, 1919.

Application filed March 12, 1919. Serial No. 282,089.

To all whom it may concern:

Be it known that I, MAX NOVICK, a citizen of the United States, and a resident of the city of New York, borough of the Bronx, in 5 the county of Bronx and State of New York, have invented a new and Improved Adjustable Bed, of which the following is a full, clear, and exact description.

This invention relates to furniture and 10 has particular reference to beds, couches, cots or the like.

Among the objects of the invention is to provide a bedstead or frame adjustable both longitudinally and laterally and provided 15 with a combined spring and mattress having similar adjustability.

Another object of the invention is to provide a bedstead and spring mattress both adjustable longitudinally and laterally and 20 with means carried by certain of the parts and coöperating with the remaining parts to make secure the adjustment in any position.

With the foregoing and other objects in 25 view the invention consists in the arrangement and combination of parts hereinafter described and claimed, and while the invention is not restricted to the exact details of construction disclosed or suggested herein, 30 still for the purpose of illustrating a practical embodiment thereof reference is had to the accompanying drawings, in which like reference characters designate the same parts in the several views, and in which—

35 Figure 1 is a plan view of my improvement.

Fig. 2 is a vertical transverse section upon the line 2—2 of Fig. 1.

Fig. 3 is a detail view corresponding to 40 the left end of Fig. 2 with the bedstead collapsed laterally and equipped with a side rail for use as a crib; and

Fig. 4 is a vertical sectional detail on the line 4—4 of Fig. 3.

45 Referring now more specifically to the drawings I show a bedstead comprising a head 10, a foot piece 11, and a spring 12. The head and foot pieces 10 and 12 are or may be substantially alike each comprising a corner posts 13 made preferably of tubular metal and of rectangular form in cross section. For convenience of description I will hereinafter employ the term "bedstead" with the understanding that such term will be applicable to any other analogous resting place. Between each pair of corner posts 13

extend telescopic rails 14 and 15, the upper rail comprising inner and outer members 14^a and 14^b connected to the corner posts respectively, while the lower rail comprises inner 60 and outer sections 15^a and 15^b similarly connected to the same posts. These telescopic members of the upper and lower rails have a fairly close sliding fit whereby positive rigidity of the bedstead will be secured even 65 though no special locking or fastening means be provided to limit or prevent the telescopic action. If desired, however, pins, bolts or other locking means might be employed to make such adjustment positive. It 70 will be understood that the rails 14 and 15 are applied to both the head and foot pieces of the bed and constitute the only transverse connections between pairs of corner posts pertaining to said head and foot pieces. The 75 rail sections 14^b and 15^b are provided with any suitable upright bars 16 such as are commonly used in this art, which when the bedstead is collapsed laterally would constitute effective closures for the head and foot 80 pieces.

The spring 12 comprises two longitudinal side rails 17 each of which consist of two telescopic members 17^a and 17^b. These side rail sections 17^a and 17^b are made of tubular 85 metal, and each of them is provided with a horizontal inwardly projecting flange distinguished from each other respectively by the numerals 18^a and 18^b. The outer rail section 17^b has an open inner side through 90 and beyond which the flange 18^a of the inner section 17^a projects, the two flanges being arranged in horizontal planes one above the other.

The head ends of the side rail sections 17^b 95 are connected by a telescopic transverse rail comprising inner and outer sections 19^a and 19^b, the connections at the ends of the side rails being rigid and the telescopic end portions of these members being connected by 100 a binding device in the form of a bolt 20 operating through one of the members and a slot 21 formed in the other. The foot ends of the sections 17^b are provided with a similar telescopic bar composed of inner and outer sections 22^a and 22^b also having a locking screw or bolt 20' operating along a slot 21. Secured to the flange 18^b of each rail section 17^b and extending between the transverse rail sections 19^a and 22^a secured to the 105 same rail section is a section 23 of a spring mattress of any suitable construction and

similarly supported upon the flange 18^b of the opposite rail and extending lengthwise between the rail sections 19^b and 22^b is another mattress section 24. These mattress sections and the rails to which they are secured constitute the length of the bedstead when adjusted to its shortest length, and when collapsed laterally the section 24 will reach substantially to the opposite rail 17^b.
10 Under normal conditions there is sufficient overlap between these spring members to provide for a double thickness thereof along the longitudinal center of the bed, an element of considerable importance in view of the fact that there is thereby provided extra strength or rigidity at that portion of the bed that is most subjected ordinarily to sagging or depression.

The foot side bar sections 17^a have secured to their foot ends transverse telescopic bar members 25^a and 25^b, the longitudinal adjustment of which is effected in the manner already described and made secure by means of a pin or bolt 20 acting through a slot 21. The forward ends of the same side bar sections have also a telescopic transverse bar comprising sections 26^a and 26^b with a binding screw 20'. The binding screws 20' may be shorter than the similar screws 20 to avoid interference with the spring members during the adjustments of the several parts provided for as described herein. Spring members 27 and 28 are carried by the two relatively adjustable parts 35 or frames of the foot portion of the mattress, these members being connected through the flanges 18^a of the side rails and extend respectively between the pairs of bars 25^a and 26^a and 25^b and 26^b longitudinally.

Any suitable means may be provided to detachably support the combined mattress and spring upon the corner posts. For this purpose I show socket pieces 29 secured one upon each side of a corner post directed toward the corner post on the same side of the

bed. The head and foot ends of the side bars 17 are likewise provided with lug or tongue members 30 adapted to fit downward into the socket pieces 29.

When the bedstead is adjusted for use as a crib I may employ a drop side panel 31 having horizontal ears 32 connected to the upper corners which coöperate with vertical rods 33. Each of these rods has a bent 55 shoulder portion 34 terminating in a head 35 projecting inward and downward through a keyhole slot 36 formed in the upper portion of each corner post directly above the socket piece 29. The lower end of 60 each rod 33 is adapted to project into any suitably arranged socket or hole such as shown at 37 formed in the lug member 30. The ear 32 has a vertical hole providing for the vertical sliding of the panel 31 along the 65 rods 33, and mounted loosely upon the lower end of the rod 33 is a finger 38 which rests normally upon the side rail and projects outward in position to support the panel 31 in elevated position, but which may be 70 swung around through 90 degrees when the side panel is to be dropped to the dotted line position shown in Fig. 3, at which time the ear 32 will rest upon the finger. When the side panels are not to be used the rods 33 75 as well as the side panels may be removed by simply lifting the rods out of the key-hole slots 36.

I claim:

In a bedstead of the character set forth, 80 the combination with a pair of corner posts on the same side of the bed each having near its upper end a keyhole slot, of a spring frame supported upon said posts, the head and foot ends of the spring frame having 85 vertical holes, vertical rods having bent shoulders and heads projected inward through said keyhole slots and having their lower ends fitted in said holes, and a drop side panel having slidable engagement with 90 said vertical rods.

MAX NOVICK.
